UNITED STATES PATENT OFFICE.

EMIL BÄCHLE, OF MERIDEN, CONNECTICUT, ASSIGNOR TO INTERNATIONAL SILVER COMPANY, OF JERSEY CITY, NEW JERSEY, A CORPORATION OF NEW JERSEY.

● DESIGN FOR AN ORNAMENT FOR VESSELS OR SIMILAR ARTICLES.

SPECIFICATION forming part of Design No. 36,449, dated July 21, 1903.

Application filed June 24, 1903. Serial No. 162,965. Term of patent 3½ years.

To all whom it may concern:

Be it known that I, EMIL BÄCHLE, a subject of the Emperor of Germany, and a resident of Meriden, in the county of New Haven 5 and State of Connecticut, have invented a new, original, and ornamental Design for Ornaments for Vessels or Similar Articles, of which the following is a brief specification, reference being had to the accompanying drawing, forming part thereof, for the special 10 and distinguishing features of the design,

and in which the figure is a plan or face view of an ornament embodying my new design.

What I claim as new, and desire to secure by Letters Patent, is—

An ornamental design for an ornament for vessels or similar articles, as shown.
